UNITED STATES PATENT OFFICE.

SIDNEY MOUNTFORD, OF NEWARK, NEW JERSEY.

TAPE-HOLDER.

SPECIFICATION forming part of Letters Patent No. 700,698, dated May 20, 1902.

Application filed October 15, 1901. Serial No. 78,702. (No model.)

To all whom it may concern:

Be it known that I, SIDNEY MOUNTFORD, of Newark, in the county of Essex, in the State of New Jersey, have invented new and useful Improvements in Tape-Holders, of which the following, taken in connection with the accompanying drawings, is a full, clear, and exact description.

This invention relates to improvements in tape-holders, having more particularly reference to that class in which the tape is automatically rewound upon the drum by a spring-motor.

The object of this invention is to produce such a device and means for manually releasing the spring so as to cause the tape to be wound upon the drum.

A further object of this invention is to provide means to allow the tape to remain unwound until such time as it may be desired to wind it.

A still further object is to so arrange and construct the component parts of the frame of the holder that they may be manufactured at a minimum cost and be easily and readily assembled by cheap labor.

To this end the invention consists in the several new and novel features of construction and operation, which are hereinafter described, and more specifically set forth in the claims hereunto annexed.

It is constructed as follows, reference being had to the accompanying drawings, in which—

Figure 1 is a perspective view of a tape-holder embodying this invention. Fig. 2 is a section on line 2 2 of Fig. 1. Fig. 3 is a view similar to that shown in Fig. 2, except that the side walls of the holder are compressed for the purpose of releasing the spring to wind the tape upon the drum. Fig. 4 is a section on line 4 4 of Fig. 2. Fig. 5 is a sheet-metal disk carrying the pinion and out of which disk the pinion is stamped. Fig. 6 is a view of the tape-drum stamped up from sheet metal. Fig. 7 is a view of the friction-post which rests within the pinion.

Similar reference characters indicate corresponding parts in all the views.

Referring now to the drawings in detail, 1 represents the side pieces of the tape-holder.

2 is the edge, the sides being provided with flanges to fit over onto the edge-piece 2, as shown in Figs. 1, 2, and 3, where they are preferably secured in any ordinary and well-known manner. 55

The parts just above described are preferably constructed of celluloid, and the edge 2 is provided with a slotway 3, through which the tape 4 extends in the ordinary way. 60

In one side of the holder I place a metallic disk 5, having two pieces 6 stamped out of the bottom to form the bearing 7. In view of the fact that these two pieces 6 are stamped from the bottom and extend at right angles 65 therefrom a slotway 8 is formed between them and midway between the two parts 6, at the base of which I place an opening 9, for the purpose hereinafter specified.

10 is a drum or cylinder stamped up from 70 a piece of sheet metal and revolvably mounted on the bearing 7, said drum having a central aperture 11 to receive the bearing 7 and provided with slotways in its periphery for the purpose of forming lips 12 and 13. 75

14 is a friction-post constructed in the form of a cross, as shown in Fig. 7, and is adapted to rest in the slotway 8, and 15 is a coil-spring mounted on the said post.

16 is a strap-spring having one end adapted 80 to engage with the lip 13 upon the drum 10 and the other end to engage and be made fast to the post 7.

The tape 4 is adapted to have its inner end secured upon the lip 12 upon the drum and 85 wound thereon and pass out through the opening 3, as shown in Figs. 1 and 4.

To assemble the parts, I first place the disk 5 within one of the sides. I then place the drum 10 over the same, letting the bearing 90 7 pass through the aperture 11. The friction-post 14 is then dropped onto the bearing 7, so that the lower end 18 will pass into the opening 9, and the lateral arms 19 engage with the slotway 8, as shown in Figs. 2 and 95 3. The spring 15 is then placed upon the upper end of the post 17, and the opposite side 1 of the tape-holder, with preferably a metallic bearing-plate 20, is placed over the same, so that when complete the parts take 100 the position shown in Fig. 2. The disk 5 is held within the case from rotation, and the

drum 10 is free to rotate upon the bearing 7, so that when the tape is withdrawn or unwound from the drum the strap-spring with-in the drum is wound up, so that it will cause 5 sufficient tension to rewind the tape when released. The lower edge of the arms 19 upon the post engage frictionally with the interior face of the drum 10, and the coil-spring 15 engages with the opposite edge of the arms 10 10 upon one end and the other end bears against the disk 20 within the tape-holder case, as shown in Figs. 2 and 3, so that a tension is normally produced to hold the lower edges of the arms 19 against the inner face 15 of the drum 10, thereby producing friction enough to normally prevent the rotation of the drum, so that when the tape is drawn out the drum will be held in any position by such friction, a suitable plate 5, of fiber or equivalent material, being interposed between the disk 5 and drum 10 to normally insure sufficient friction between said parts to hold the drum from rotation. When it is desired to remove this friction, and thereby release the 25 drum, so that it may operate by power of the spring, the sides of the tape-holder are compressed centrally and take the position shown in Fig. 3, one of the sides coming in contact with the lower end 18 of the post 14 and forcing the lateral arms 19 out of engagement with the bottom face of the drum 10, thereby allowing it to rotate and rewind the tape upon the drum.

In the foregoing drawings I have shown 35 means for securing the ends of the strap-spring to the drum and to the pinion 7 and also means for securing the end of the tape upon the periphery of the drum; but I do not wish to be limited to this precise form of 40 construction or the precise form of construction of any other parts shown in the drawings, as it will be evident that they may be varied and modified at will without departing from the spirit of my invention.

45 Having described my invention, what I claim, and desire to secure by Letters Patent, is—

1. A tape-holder comprising a case having a tape-opening, a rotary spring-actuated tape-holding drum in the case, a friction-surface for the drum, an axially-movable member and a spring operating to force the drum into frictional engagement with said surface, said member having an extension adapted to be engaged by one of the end walls of the case whereby the compression of said wall moves the member against the action of its spring to release the drum.

2. A tape-holder comprising a case having 60 a tape-opening, a hollow bearing, a friction-surface, a spring-tensioned brake member movable axially in the bearing, a spring-actuated drum normally impinged between the friction-surface and brake member and car-

rying a tape movable through said opening, 65 and a yielding portion forming part of the case arranged to be compressed against the brake member to move the same against the action of its spring to release the drum.

3. A tape-holder comprising a case, opposite disks within the case, a hollow bearing projecting from one of the disks, a spring-rotated drum mounted on the bearing and carrying a tape, a friction-surface between the drum and one of the disks, a brake member 70 and its actuated spring between the drum and other disk to normally hold said drum in engagement with said surface, and means on the case to engage and move the brake end-wise against the action of its spring to release 75 the drum.

4. A tape-holder comprising a case having a tape-opening, a bearing within the case having longitudinal slotways, a spring-actuated drum rotatably mounted on said bearing and carrying a tape to be wound thereon, a post having lateral arms mounted in said bearing, said arms adapted to rest normally in frictional contact with one face of the drum and means for forcing said arms out of frictional 80 contact with the drum for the purposes specified.

5. A tape-holder comprising a case having a tape-opening, a bearing within said case having longitudinal slotways, a spring-actuated 85 drum rotatably mounted on said bearing and carrying a tape adapted to be wound thereon, a post having lateral arms mounted in said bearing, said arms engaging with the slotways and resting normally in frictional 90 contact with one of the faces of the drum, a spring mounted on said post, one end engaging with said arms and the other end with the wall of the case for the purpose of holding said arms in frictional contact with the 95 drum for the purposes specified.

6. A tape-holder comprising a case having a tape-opening, a tubular bearing within said case having longitudinal slotways, a spring-actuated drum rotatably mounted on said bearing and carrying a tape adapted to be wound thereon, a post having an axially-extending arm adapted to be engaged by the adjacent wall of the case and lateral arms mounted in said bearing, said arms engaging 110 with said slotway and resting normally in frictional contact with one of the faces of the drum, a spring mounted on said post within the bearing, one end engaging with the said arms and the other end against the wall of 115 the case for the purposes specified.

In witness whereof I have hereunto set my hand on this 8th day of October, 1901.

SIDNEY MOUNTFORD.
